US0D1088737S

(12) **United States Design Patent** (10) **Patent No.:** **US D1,088,737 S**
(45) **Date of Patent:** **** Aug. 19, 2025**

(54) **LIQUID CONTAINER**

- (71) Applicant: **Cool Gear International, LLC**,
Plymouth, MA (US)
- (72) Inventor: **John Mason**, Brockton, MA (US)
- (73) Assignee: **Cool Gear International, LLC**,
Plymouth, MA (US)
- (**) Term: **15 Years**
- (21) Appl. No.: **29/868,609**
- (22) Filed: **Dec. 8, 2022**
- (51) LOC (15) Cl. **07-01**
- (52) U.S. Cl.
USPC **D7/536**
- (58) **Field of Classification Search**
USPC D7/396.2, 394, 507, 509-511, 514,

(57) **CLAIM**

The ornamental design for a liquid container as shown and described.

DESCRIPTION

FIG. 1 is a first perspective view of a liquid container, showing my new design;

FIG. 2 is a second perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1; and,

FIG. 8 is a bottom view of the design of FIG. 1.

The broken lines shown in the drawings are included for the purpose of illustrating the unclaimed portions of the liquid container. The broken lines form no part of the claimed design.

1 Claim, 8 Drawing Sheets
